UNITED STATES PATENT OFFICE.

INMAN TUCKER, OF YUBA CITY, CALIFORNIA.

RAISIN-CLEANING MACHINE.

1,232,126.

Specification of Letters Patent.

Patented July 3, 1917.

Application filed January 4, 1916. Serial No. 70,222.

To all whom it may concern:

Be it known that I, INMAN TUCKER, a citizen of the United States, residing at Yuba City, in the county of Sutter and State 5 of Calif., have invented certain new and useful Improvements in Raisin-Cleaning Machines, of which the following is a specification.

This invention relates to improvements 10 in machines for cleaning raisins and the like, and more particularly to the type of machine embodied in Patent No. 1,170,026, February 1, 1916.

The object of the invention is to simplify 15 the construction and operation of certain component parts of the machine.

To the accomplishment of the recited object, and others coördinate therewith, the preferred embodiment of my invention resides 20 in the construction and arrangement of parts shown in the accompanying drawings, hereinafter described and embraced within the scope of the appended claims.

In said drawings:

25 Figure 1 is a side elevation, partly in section, of the complete machine.

Fig. 2 is a fragmentary perspective view of the toothed combing and elevating bar.

Fig. 3 is a view in perspective of the sus- 30 taining bar for the guide rods.

Figs. 4 and 5 are sectional views of mod- ifications.

Fig. 6 is a detailed perspective of a por- 35 tion of the toothed bar and shaft.

And Fig. 7 is a detail perspective view showing the tooth reversed.

In my original application there is disclosed 40 a plurality of individually operable combing and elevating fingers, which by means of certain tripping mechanism have imparted to them a slight "kick." As explained in the specification this "kick" combined with the force of the air blast serves to carry away the foreign particles over the 45 edge of the butting board. I have found that by slightly increasing the force of the air blast and eliminating the "kick" together with the mechanism used to produce such movement of the fingers that all extraneous matter can be separated from the raisin pack 50 very satisfactorily, thereby effecting considerable saving in parts as well as reducing to a minimum the likelihood of the machine becoming inoperative. I have devised 55 three simple ways in which this result may be accomplished, and in each instance the

combing and elevating teeth are fixed or rigid and operate as a unit with respect to the foraminous cradle which contains the raisin pack.

In the drawings, 5 represents the frame, 6 the conveyer leading to the hopper 7, 8 the foraminous cradle and 9 the blower provided with a spout 10, all of which parts are specifically described in my original application. Referring particularly to Fig. 1, it will be seen that I mount a reversible eccentric shaft 11 transversely of the frame 5 above the hopper 7. Loosely fitted to and depending from the opposite proximal ends of the shaft are a pair of hangers 12 which are rigidly connected to the guide rods 13 at their lower extremities. These rods support a transversely disposed bar 14 carrying a plurality of teeth 15, and at their upper free extremities operate in slots 16 of the sustaining bar 17. When motion is imparted to the pulley 18 of the shaft 11, the rods 13 serve to guide the toothed bar 14 and at the same time cause the teeth to de- 70 75 80 85 90 95 100 105 110

scribe an ellipse.

In Figs. 5 and 6, the guide rods are eliminated entirely and the toothed bar 14 is secured upon one side of a straight shaft 19 supported by the depending bearings 20. 85 Bolts 21 or equivalent fastening means may be used as fastening means. In this modification the sweeping movement of the teeth is made possible by the eccentric location of the bar relative to the square shaft.

The modification exhibited in Fig. 4 comprises a drum 22 provided with peripherally arranged teeth 23 mounted in the bearings 20. This form is devoid of any means for effecting a sweeping movement, but in all of the forms it will be seen that the teeth are curved at their lower extremities, and are adjustably attached so that they may be reversed to correspond with the direction of rotation of the shaft.

In operation the cradle is reciprocated in a horizontal plane, thus alternately forcing the pack of raisins rearwardly and forwardly of the cradle. The mechanism is so timed that the teeth, when rotated, will operate upon the pack while it is disposed rearwardly of the cradle, combing and elevating the raisins to a point adjacent the butting board or end of the chute 24, where the foreign matter is blown by the blast issuing from the spout 10 and passing through the uncovered perforations in the

front of the cradle over the end of this butting board.

Under some circumstances, I have found that it is highly desirable to reverse the direction of rotation of the shaft so that the material to be acted upon will be carried toward and in direct opposition to the air blast, thereby effecting a more positive separation of the foreign matter, and the like.

13 In this case, the position of the teeth may be reversed to facilitate the operation.

What is claimed is:

1. In a machine of the class described, the combination of a foraminous cradle, 15 adapted to hold raisins, or the like, to be cleaned, means for causing the raisin pack to be moved alternately rearwardly and forwardly of said cradle, a reversible shaft, reversible teeth movable as a unit with said 20 shaft and adapted to comb and elevate the raisins while the raisin pack is disposed forwardly or rearwardly of said cradle, and means for supplying an air blast to the raisins through the uncovered perforations 25 in the front of the cradle.

2. In a machine of the character described, the combination of a foraminous cradle, means for agitating said cradle, a reversible shaft disposed transversely above and adjacent said cradle, reversible teeth 30 movable as a unit with said shaft, and adapted during a portion of their movement to operate within the confines of said cradle, and means for supplying an air blast to said cradle.

3. In a machine of the character described, the combination of a foraminous cradle, means for agitating said cradle, means for supplying an air blast to said cradle, a shaft disposed transversely above 40 and adjacent said cradle, combing and elevating means associated with said shaft and operable in the cradle in a direction opposed to the direction of said air blast.

In testimony whereof I hereunto affix my 45 signature in presence of two witnesses.

INMAN TUCKER.
